UNITED STATES PATENT OFFICE.

ISAAC P. DRAWBAUGH, OF DE QUEEN, ARKANSAS.

ELEVATOR SAFETY DEVICE.

1,169,015.

Specification of Letters Patent.

Patented Jan. 18, 1916.

Application filed May 24, 1913. Serial No. 769,670.

To all whom it may concern:

Be it known that I, ISAAC P. DRAWBAUGH, citizen of the United States, residing at De Queen, State of Arkansas, have invented 5 certain new and useful Improvements in Elevator Safety Devices, of which the following is a specification.

This invention relates to an improved apparatus to be used as an emergency brake for 10 the car or cage of an elevator shaft.

The primary object of the invention is to provide simple and inexpensive means for positively and automatically stopping the elevator car or cage should the lifting cable 15 become broken or the operating mechanism deranged.

A further object of the invention resides in the provision of pneumatic means arranged upon the top of the car or cage to act 20 as a cushion therefor, this arrangement absorbing the shock and jolt that would otherwise be manifest were the said means not provided.

The invention still further resides in the 25 provision of a safety attachment for elevators which may be applied to the cars or cages of the ordinary construction without altering or changing the car to any material extent.

30 The above and additional objects are accomplished by such means as are illustrated in their preferred embodiment in the accompanying drawings, described in the following specification and then more particularly 35 pointed out in the claims which are appended hereto and form a part of this application.

In describing my invention in detail reference will be had to the accompanying drawings, wherein like characters denote like or 40 corresponding parts throughout the several views, and in which:

Figure 1 is a side elevation, one of the compressed air cylinders being shown in section of a device constructed in accordance with 45 my invention, the car or cage of the elevator being broken away; Fig. 2 is a top plan view of the brake operating mechanism, the elevator guides being shown in section; Fig. 3 is a section on line 3—3 of Fig. 2; Fig. 4 is an 50 end view illustrating the arrangement of the brake shoes; Fig. 5 is a detail perspective view of one of the brake shoes; and Fig. 6 is an enlarged section on line 6—6 of Fig. 2.

Referring now to the drawings, wherein is 55 illustrated the preferred form of my invention the numeral 1 designates the elevator

cage or car to which is secured in any suitable manner a pair of vertically extending cylinders 2, the said cylinders being disposed upon the top of the car or cage, one near each 60 side thereof, and provided with a piston rod 3 having a piston 4 secured to its lower extremity within the cylinder 2. The rods 3 are secured to a suitable metallic casing 5 through the medium of nuts 6 arranged over 65 the upper extremities of the said rods, the latter projecting from the cylinders at the top thereof and extending through the casing 5 as is clearly shown in Fig. 1 of the drawings. The usual guide beams 6' are positioned one upon each side of the elevator car, the said beams extending throughout 70 the entire length of the elevator shaft for guiding the elevator during its travel. Cut out portions 7 are formed within the extremities of the casing 5 within which the guide beams 6' are fitted, the said beams adapted to frictionally engage suitable brake shoes 8 dove-tailed as at 9 within the casing ends 5, one upon each side of the cut out 75 portions 7 formed therein, the mechanism for operating the said brake shoes to be hereinafter fully described.

A shaft 10 extends across the elevator shaft and is journaled within suitable bearings 11, the latter being adjustably secured as at 12 to the casing 5 so as to position the extremities of the shaft adjacent the guide beams 6' of the elevator mechanism. Rollers or friction wheels 13 are keyed or otherwise 90 secured upon the extremities of the shaft 10 and are adapted to frictionally engage the sides of the guide beams 6' for imparting rotary movement to the shaft 10 during the travel of the elevator car throughout the 95 length of the shaft. A governor, designated in its entirety by the numeral 14 is arranged upon the shaft 10 near one end thereof, the said governor comprising the usual weight members 15 pivotally secured to suitable 100 arms 16 in turn pivotally secured to a bracket 17 fixedly secured to the shaft 10. A second pair of arms 18 are pivotally secured to the weight members 15 and extend to a second bracket 19 slidably arranged over the said shaft 10 and normally held in spaced relation to the stationary bracket 17 through the medium of an expansion spring 20 arranged over the said shaft, one end of which engages suitable lock nuts 21 threaded on 110 the said shaft while its opposite end bears against the said slideable bracket 19.

The means for operating the brake shoes 8, the said means being controlled by the rotation of the governor 14, comprises a pair of bell crank levers 22, the said levers being pivotally secured as at 23 within a cut out portion 24 of the casing 5, one near each end thereof or adjacent the guide beams 6'. The said two levers 22 being in duplicate, but one will be described in detail. A pair of segmental racks 25 are formed integrally with the bell crank lever 22, the said racks being arranged in spaced relation so as to engage rack bars 26 formed upon the brake shoes 8 and extending throughout the entire length of the inner face thereof. The said racks 25 are normally held in mesh with the rack bars 26 through the medium of a trigger arm 27 broken centrally as at 28 to permit pivotal movement thereof and terminative at its lower extremity in a longitudinally extending rod 29 journaled within suitable brackets 30 arranged upon the upper face of the casing 5 and extending to a point above the said casing adjacent the said members 15 of the governor, the opposite end of the said rod from that of the trigger arm 27 being provided with a lever 31 adapted to be engaged by lugs 32 formed upon the said weight members 15 of the governor as the latter are rapidly revolved in a manner to be hereinafter fully set forth. The inner or free ends of the bell crank levers 22 are normally supported by the trigger arm 27 of the trip mechanism, this arrangement holding the racks 25 inoperative with respect to the rack bars 26 of the brake shoes. Springs 33 are secured to each of the levers 22 for rocking the said levers or swinging the same upon their pivot supports 23 when the trigger arm 27 is withdrawn from engagement with the free ends of the said levers, the tension of the springs moving the racks 25 and lifting the brake shoes 8 so as to wedge the same between the guide beams 6' and the extremities of the casing 5 as is clearly shown in Fig. 4 of the drawings. To increase the frictional engagement between the said shoes and the guide beams 6' the engaging faces of the said shoes 8 are serrated as at 34.

Having described in detail the construction of the apparatus or device, the operation of the same will now be fully set forth. Should the supporting cable or rope of the elevator car for any reason break, or should the operating mechanism become deranged, the weight of the car or cage will cause the same to drop or fall, this movement of the car rapidly rotating the friction rollers 13, in turn imparting a like movement to the shaft 10. As the shaft 10 rotates abnormally fast the weight members of the governor 14 expand until the lugs 32 thereof engage the lever 31, such engagement throwing the trip arm 27 out of engagement with

the free ends of the operating bell crank levers 22. The free extremities of the bell crank levers being unsupported the tension of the springs 33 will swing the racks 25 upon their pivotal support, this movement of the racks elevating the brake shoes 8 and wedging the same between the inner faces of the cut out portions 7 and the guide members 6' and thus preventing further movement of the car 1.

To absorb the shock and relieve the strain upon the casing 5 and the mechanism carried thereby, the compressed air cylinders 2 have been provided. As the brakes are applied in the manner above set forth the said cylinders 2 are free to move upon the piston rods 3 which are stationary and as the piston 4 is drawn toward the upper extremity of the said cylinders the air contained within the latter is compressed thereby forming a cushion for the car body and preventing serious injury to the occupants thereof.

It will be seen from the above, taken in connection with the accompanying drawings that the entire brake mechanism is controlled by the rotation of the friction rollers 13, the normal rotation of which will cause the weight members 15 of the governor to rotate free from engagement with the lever 31 of the trip mechanism; that the moment the lever 31 is engaged by the said weight members the trigger arm 27 is withdrawn from engagement with the free ends of the operating levers 22; and that the provision of the springs 33, disposed as they are with respect to the said operating levers, will operate the segmental racks 25 and vertically slide the brake shoes until the same become wedged against the guide beams 6' of the elevator mechanism.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. An emergency brake for elevator cars including a plurality of friction rollers, guide beams upon which the rollers ride, rack carrying brake shoes movable into and out of engagement with said beams, and means controllable by movement of said rollers adapted to engage the shoe racks to force the shoes against the beams.

2. An emergency brake for elevator cars including a wedge shaped shoe, teeth formed upon the shoe, a guide beam extending longitudinally of the elevator shaft, a segment 5 engaging the teeth of said shoe, means normally maintaining the segment inoperative, means controlled through movement of the elevator to actuate said last mentioned means, and means operating automatically 10 to move the shoe in engagement with the beam upon a release of the control means for the segment.

3. An emergency brake for elevator cars including a pair of wedge shaped shoes, 15 guide beams extending longitudinally of the elevator shaft, teeth formed upon the respective shoes, a segment engaging the teeth of each shoe, trip means normally maintaining the segments inoperative, and means controlled through movement of the elevator car to actuate said trip means to provide 20 for movement of the respective shoes into engagement with the respective guide beams, as and for the purpose set forth.

25 4. An emergency brake for elevator cars including a wedge shaped shoe, teeth formed upon the said shoe, a guide beam extending longitudinally of the elevator shaft, a segment engaging the teeth of said shoe, trip means 30 normally maintaining the segment inoperative, a friction roller engaging the said beam, and means controlled through movement of said roller to actuate said trip means and provide for movement of said 35 shoe in engagement with said beam.

5. An emergency brake for elevator cars including a pair of wedge shaped shoes, teeth formed upon the respective shoes, 40 guide beams extending longitudinally of the elevator shaft, a segment engaging the teeth of each shoe, spring actuated levers rigid with the respective segments, trip means engaging the respective levers to hold the latter inoperative, and means controlled 45 through movement of the elevator car to actuate said trip means.

6. An emergency brake for elevator cars including a pair of brake shoes, guide beams extending longitudinally of the elevator 50 shaft, means engaging said shoes for moving the latter into frictional engagement with the respective guide beams, trip means nor-

mally holding said last mentioned means inoperative, friction rollers engaging the respective beams, and governor mechanism 55 operable through movement of the friction rollers to actuate said trip means.

7. An emergency brake for elevator cars including a pair of wedge shaped shoes, teeth formed upon the respective shoes, 60 guide beams extending longitudinally of the elevator shaft, a segment engaging the respective teeth of the said shoes, said segments being actuatable to move the said shoes into frictional engagement with the 65 respective beams, a lever rigid with each segment, means normally holding the levers in a position whereby to render said segments inoperative, spring means operating automatically to actuate the segments 70 upon a release of the said levers, rollers adapted for frictional engagement with the said beams, governor mechanism controlled through rotation of said rollers, the said governor mechanism being actuatable to 75 operate said trip means and release said levers.

8. An emergency brake for elevator cars including a pair of wedge shaped shoes, teeth formed upon the respective shoes, 80 guide beams extending longitudinally of the elevator shaft, a segment engaging the teeth of each shoe, a lever rigid with each segment, spring means engaging the respective levers to actuate said segments and 85 move said shoes simultaneously into engagement with the respective beams the moment said levers are released, trip means normally maintaining the levers inoperative, rollers adapted for frictional engagement 90 with the respective beams, governor mechanism actuatable through rotation of said rollers, the said governor mechanism being engageable with said trip mechanism when rotated at a predetermined speed to 95 actuate said mechanism and release said levers to provide for movement of the respective shoes, as and for the purpose set forth.

In testimony whereof I affix my signature in presence of two witnesses.

ISAAC P. DRAWBAUGH.
